US00D756234S

(12) **United States Design Patent**
Orset

(10) **Patent No.:** **US D756,234 S**
(45) **Date of Patent:** **** May 17, 2016**

(54) **BOTTLE WITH CAP**

(71) Applicant: **CELGENE CORPORATION**, Summit, NJ (US)

(72) Inventor: **Frederic Eugene Lucien Orset**, Habere-Lullin (FR)

(73) Assignee: **Celgene Corporation**, Summit, NJ (US)

(**) Term: **14 Years**

(21) Appl. No.: **29/502,019**

(22) Filed: **Sep. 10, 2014**

(51) **LOC (10) Cl.** **09-01**

(52) **U.S. Cl.**

CLAIM

The ornamental design for a bottle with cap, as shown and described.

DESCRIPTION

FIG. 1 is an exploded top, first side and second side perspective view of a bottle with cap showing my new design;
FIG. 2 is a top, first side and second side perspective view thereof;
FIG. 3 is a bottom, first side and second side perspective view thereof;
FIG. 4 is a first side elevational view thereof;
FIG. 5 is a second side elevational view thereof;
FIG. 6 is a third side elevational view thereof;
FIG. 7 is a fourth side elevational view thereof;
FIG. 8 is a top plan view thereof; and,
FIG. 9 is a bottom plan view thereof.

1 Claim, 4 Drawing Sheets
